UNITED STATES PATENT OFFICE.

GEORGE E. NOBLE, OF CHEHALIS, WASHINGTON, ASSIGNOR TO EDWIN H. LUKE, OF SEATTLE, WASHINGTON.

SPLIT SHINGLE.

Application filed August 1, 1927. Serial No. 209,854.

My invention relates to a split shake or shingle. In particular, it is an improvement upon the shingle disclosed in the application of Frank L. Dietz, Serial Number 153,889, filed December 10, 1926, and upon Mr. Dietz's process for splitting out these shingles.

In operating according to the Dietz process, the shakes which are split out are always tapered, but occasionally, due to peculiarities of grain in a certain piece, or in a certain spot of a given piece, or due perhaps to inaccuracy of the splitter, the shakes will taper out to a feather edge and will, perhaps, leave a jagged corner, which renders the shake of second grade. It is an object of this invention to provide a method of splitting, and to produce a shingle, in which the production of such seconds is almost wholly eliminated, and a method by means of which the thickness of the tip of the shakes or shingles can be controlled as accurately as the thickness of the butts.

A further object is the elimination of grossly irregular surfaces, though still retaining the naturally split appearance, whereby the laying of the shakes is made easier, and whereby they will fit more closely upon one another, and thus keep the roof tighter.

My invention comprises the novel process and the novel product thereof, the product being illustrated in the accompanying drawings and the steps of the process being illustrated by diagrams, and both product and method being disclosed in this specification and more particularly defined by the claims terminating the same.

In the accompanying drawings illustrating my improved process and product,—

Figure 1 is a perspective view of a shake or shingle embodying my invention and made in accordance with my process.

Figure 2 is a side elevation of the same.

Figures 3, 4 and 5 are cross sections on the respective lines 3—3, 4—4 and 5—5 of Figure 2 at the tip, intermediate portion, and butt of a shingle.

Figure 6 is a plan view of a block, of which Figure 7 is a side elevation, and Figures 8 and 9, 10 and 11 are similarly plan views and side elevations, illustrating the several steps in my process.

In this specification I shall employ the term "shake" or "shingle" interchangeably,

for, as the description progresses, it will become apparent that my method is adapted to the splitting out of true shakes which, properly speaking, are boards of substantially uniform thickness throughout, or to the splitting out of true shingles, which are boards tapering from butt to tip. Broadly speaking, my invention relates to the establishment, prior to splitting, of the thickness of the board to be split, at each end; hence, if a shingle is to be split out in accordance with the Dietz method, it may be determined in advance just what thickness the tip will assume, or, if a true shake is to be split, the thickness of the two ends of the shake may be established before the shake is split out, so that it may be of substantially uniform thickness, and so that it will be substantially plane adjacent the ends and upon both faces.

As in the Dietz process, when my process is employed in the splitting out of tapered shakes or shingles, they are split from the block tapering, so that no finishing action is required, so that all of the wood is used, and so that none is wasted.

According to my method, a block of suitable wood, generally one which splits easily, such as western red cedar, is placed on end, and after the first or outside board is split off, the block, instead of being immediately upended as taught in the Dietz application, is scored across its end to define the thickness of tip in the next shingle. Thereafter, it is reversed end for end and is split out, starting with the thickness of butt desired in the next shingle, and this split will run out and eventually run into the split started from the previous end, so that the thickness of tip in the shingle will be that determined by the first preliminary scoring of the one end, and the thickness of butt will be that determined by the splitting starting from the opposite end.

Thus, as illustrated in Figures 6 to 11, inclusive, the block 1 first had a board taken off of the face 12, and, subsequently, had the frow 2 placed across its end 10 close to the face 12, and a split 13 was started. The frow, however, was immediately withdrawn, and the split 13 extends only a short distance inward of the end 10. The block is now upended, and, we find it in the position shown in Figures 6 and 7, resting upon its end 10, the end 11 being uppermost. Note, too, that it is placed so as to cut vertical

grain shingles. It is placed back from the corner 14 by an amount equal to the thickness of butt desired in the finished shingle, and the frow is then driven through the block from the end 11 towards the end 10.

Note that the splitting progresses in advance of the frow 2. The edge of the frow is not a cutting tool and does not shave the material. Rather, the frow acts as a wedge 10 to split or part the fibers of the wood in advance of it. In accordance with the Dietz invention, it will be evident that the split 15 now started by the frow 2 will tend to taper out toward the corner 16, but will eventually 15 meet or intersect the split 13, whereupon the shingle will split off of the block and there will be formed a shingle which is substantially uniformly tapered from a perfect butt to a perfect tip.

20 The next step, as shown in Figures 8 and 9, is to place the frow along the line 17' inward from the new upper edge 16' by an amount equal to the thickness of tip desired in the next shingle. It is entered again, as 25 seen in Figure 9, the new split 13' extending only part way of the length of the block. The frow is then withdrawn (although there is no reason why it might not remain in place except as it would tend to continue 20 the split farther), and the block is then upended to bring the end 10 uppermost, as seen in Figures 10 and 11. The frow is now placed back of the edge 14', now uppermost, by an amount equal to the thickness of butt 25 desired in the new shingle, and is driven through the block as before, whereupon the split 15' will intersect with or coincide with the split 13', to form again a perfect and uniformly tapered shingle.

40 Referring to Figures 1 to 5, inclusive, it will be seen that shingles thus formed have corners 14 and 24 at the butt, and which are both true straight edges, and which are substantially parallel. Moreover, the upper 45 and lower surfaces, just inward of these corners, are substantially plane, for each of these surfaces has been defined originally by the entrance of the frow. Moreover, at the tip the edges 16 and 26 are true straight 50 edges, substantially parallel to each other and to the edges 24 and 14, and the surfaces immediately inward thereof are substantially plane, these too having been formed by the entrance of the frow.

55 The continuation of the split 13 can sometimes be observed, but this is of little moment. It does not extend far, and, in fact, is scarcely noticeable. In any event, as the shingles are laid in a roof, this split and any 60 feather edge which may result therefrom is beneath one or two courses of shingles thereabove, and thus is held tightly against the wood beneath and is protected.

It will be understood by those skilled in 65 the art that the split 15 or 15' is accom-

plished by entering the frow, and then using it as a pry to split the fibers, and this operation frequently leaves slight transverse frow marks on the surfaces of the wood with which the frow contacts. These frow marks are illustrated at 18 in Figure 1, in a somewhat exaggerated fashion. They are not deep, and, as mentioned above, are scarcely noticeable. They are shown in the drawing in order that it may be understood how the shingle is split out, and as a guide to indicate from which end the shingle was split out with the frow 2.

What I claim as my invention is:

1. A rived shake tapering from a butt to a thinner tip, the butt thickness and the tip thickness being uniform throughout the width of the shake. 80

2. A rived shake tapering from a butt to a thinner tip, the tip and butt edges being straight. 85

3. A rived shake tapering from a butt to a thinner tip, the two butt end edges being straight and parallel to each other, and the two tip edges being likewise straight and parallel to each other. 90

4. A rived shake tapering from a butt to a thinner tip, the two butt end edges being straight and parallel to each other, and the two tip edges being likewise straight and parallel to the butt edges. 95

5. A rived shake tapering from a butt to a thinner tip, both the upper and lower faces, at butt and at tip, being substantially plane and in nearly parallel planes. 100

6. A hand-split shake, the upper and lower faces having the naturally split surface extending substantially from end to end, and both the upper and lower faces, immediately at each end, being substantially plane. 105

7. A shake tapered substantially uniformly from butt to tip, and both faces presenting a generally rough, naturally split surface, each end of both faces being substantially plane, and merging into the rough surface. 110

8. A shake tapered from butt to tip, and having upper and lower surfaces naturally split, and its tip of uniform thickness across its entire width. 115

9. The method of splitting shales which consists in splitting successive shales from opposite ends of the blocks, initially scoring the end of the next shale at one end of the block before reversing the block to split off this shale from the opposite end. 120

10. The method of splitting shales which consists in scoring one end of a shale in the uppermost end of a block, reversing the block and splitting off this shale from the opposite and now uppermost end, scoring the end of the next shale in the same end and at the same side of the block, then reversing 125 130

the block to split off the second shake from the opposite end, and so on until the block is consumed.

11. The method of splitting tapered 5 shakes which consists in splitting butts of successive shakes alternately from opposite ends of the block, and scoring the tip end of each shake prior to commencing to split from the butt end.

10 12. The method of splitting tapered shakes from a wooden block which consists in entering a wedge into an end of the block and spaced from its edge by an amount equal to the tip thickness desired, to define the

tip, reversing the block and driving the 15 wedge into the opposite end and at the same side of the block, and spaced from the edge by an amount equal to the butt thickness desired, forcing the wedge endwise through the block, then similarly, in succession, defining the tip and the butt of the next shake at the same side, but at opposite ends, and forcing the wedge through the block from the end opposite the first. 20

Signed at Chehalis, Lewis County, Wash- 25
ington, this 21st day of July 1927.

GEORGE E. NOBLE.
